BOAT HULL

Harold S. Hollnagel, Milwaukee, Wis.

Application July 22, 1957, Serial No. 47,045

Term of patent 14 years

(Cl. D71—1)

Figure 1 is a top plan view of a boat hull embodying my new design.

Figure 2 is a bottom plan view of the same.

Figure 3 is a side elevational view of the boat hull.

Figure 4 is a vertical cross-sectional view on line 4—4 of Figure 1.

Figure 5 is a rear elevational view thereof.

Figure 6 is a view taken on line 6—6 on Figure 1.

Figure 7 is a fragmentary cross-section on the line 7—7 of Fig. 1.

I claim:

The ornamental design for a boat hull, as shown.
